(57) CLAIM

The ornamental design for a shoe, as shown and described.

DESCRIPTION

FIG. 1 is a front perspective view of a shoe showing my new design;
 FIG. 2 is a side view thereof;

FIG. 3 is a rear perspective view thereof;

FIG. 4 is a front perspective view of a shoe showing an alternate embodiment of my new design;

FIG. 5 is a side view thereof; and,

FIG. 6 is a rear perspective view thereof.

The six small broken line circles within the shaded area represent eyelets that form no part of the claimed design. The even-length broken lines in FIGS. 1-3 represent stitching that forms no part of the claimed design. The uneven-length broken lines depicting the remainder of the shoe form no part of the claimed design.
